UNITED STATES PATENT OFFICE

93,143

DESIGN FOR A TIE RACK

George D. Spragg, Bellaire, Ohio

Application May 21, 1934, Serial No. 51,875

Term of patent 3½ years

To all whom it may concern:

Be it known that I, GEORGE D. SPRAGG, a citizen of the United States, residing at Bellaire, in the county of Belmont, State of Ohio, have invented a new, original, and ornamental Design for a Tie Rack, of which the following is a specification, reference being had to the accompanying drawing, in which

I claim:—

The ornamental design for a tie rack, as shown. In testimony whereof, I affix my signature.

GEORGE D. SPRAGG.
